PIPE HOLDER

Joseph E. Jackson, Memphis, Tenn., assignor
to Wendell Palfrey, Memphis, Tenn.

Application August 1, 1938, Serial No. 222,433

6 Claims. (Cl. 206—41)

This invention relates to holders which are detachably securable to cans of smoking tobacco for the purpose of holding the smokers pipe when not in use.

5 Tobacco, as is well known, is often sold in tin cans which are of a convenient size and shape to go in the pocket. Many smokers carry their pipes about with them, sometimes using a cover for them, but eventually merely sticking them 10 in their pockets where they are more or less of a nuisance.

The objects of the present invention are:

To make a holder which can be readily attached to the side of a can of tobacco and into 15 which the pipe may be slipped to hold it with reasonable firmness against the can, usually in a position in which the bowl of the pipe overlies the top of the can.

A further object is to make a holder which 20 may be readily detached from the can, as for instance after the content has been used up, and attached to a full can.

A further object is to make a holder which 25 will frictionally hold the pipe with reasonable firmness; and

A still further object is to make a holder which in inexpensive and of ornamental design.

The means by which the foregoing and other objects are accomplished and the manner of 30 their accomplishment will readily be understood from the following specification on reference to the accompanying drawing, in which:

Fig. 1 is a side elevation of a tobacco can with 35 portions of top and bottom corners cut away in section, the holder being shown in sectional elevation; dash lines indicating the general contour of a pipe held in place by the holder.

Fig. 2 is a side elevation of the same holder.

Fig. 3 is an elevation taken at right angles to 40 Fig. 2; and

Fig. 4 a corresponding plan view.

Figs. 5 and 6 are elevations showing a modified form of pipe gripping members, Fig. 5 being a side elevation and Fig. 6 an elevation at right angles thereto.

Figs. 7 and 8 are similarly related elevations of a still further modified form of the device.

Referring now to the drawing in which the various parts are indicated by numerals:

50 10 is a tobacco can having an openable lid 11 forming an upper end closure. 12 is the bottom of the can, and 13 a rib formed by the interlocking of the bottom and sides of the can, this rib projecting slightly below the level of the bottom 12 in usual manner. The edges 14 of

the can are as is usual, arcuate in cross section.

The holder comprises an elongated body portion 15 of thin sheet metal or other material, arcuately curved to conform to the shape of the edge of the can. 16 is a hook formed on the upper end of the body portion and adapted to be engaged with the upper edge of the can when the cover is open. The hook preferably is quite flat so that the lip 17 of the hook will lie close to the inner surface of the can when the holder 10 is in place thereon. At the bottom end the holder has an inwardly extending lug 18 adapted to underlie the bottom of the can and rest thereagainst, this lug preferably has an upwardly protruding button 19 engageable over the rib 13 to 15 secure the bottom end of the holder in place.

20 20 are oppositely disposed portions of the sides of the body 15, which portions are reversely bent and folded back along the sides of the holder, these extensions projecting beyond the body of 20 the holder to form a pair of oppositely disposed converging jaws adapted to grip the sides of the pipe stem and snugly hold the pipe in place against the holder and can.

In that form of the device shown in Figs. 5 and 6 the body 15—A and engaging structure is quite similar to that before described, except that fingers 25 have been cut from the body, these fingers extending alternately from opposite sides of the body and converging so as to provide jaws 30 adapted to grip the side edges of the pipe stem as before and securely hold same.

In Figs. 7 and 8 the body 15—B of the holder is formed substantially as before. 30 is a trough shaped sleeve adapted to be spaced away from the body to permit insertion of the pipe stems. The edges 32 of this trough may be flanged and secured to the edges 33 of the holder as by rivets 34 or otherwise. 35 is a resilient tongue cut from the sleeve and inwardly depressed so as to frictionally engage a pipe stem placed therein.

In using the device the tobacco can is opened, the hook 17 is engaged over the top edge and pushed down to place, the bottom lug 18 is pushed in, the button 19 slipping over the rib 13 and engaging against the bottom of the can and the holder is ready for use. After the holder is placed, the can may be closed and subsequently opened and closed with substantially no interference from the holder. The pipe may be slipped into place between the gripping jaws and removed therefrom at will in obvious manner.

I claim:

55 1. In a pipe holder for use with a tobacco can, an elongated arcuate body of thin material con-

- forming to the arcuate curvature of the can edge, said body having a hook shaped end adapted to engage over the top edge of the opened can, and a deformed lug at its opposite end adapted to 5 inter-engage with the bottom of said can; and means intermediate the length of said body extending outwardly therefrom, and cooperating with said body to engage the stem of said pipe, said means including at least one resilient tongue.
- 10 2. In a pipe holder for use with a tobacco can, an elongated arcuate body of thin metal having a can engaging hook at one end and a can engaging lug at its opposite end, both extending inwardly toward said can, and means extending beyond said body and intermediate its length cooperating with said body to grip the stem of said pipe, said means including at least one resilient tongue.
- 15 3. In a pipe holder for use with a tobacco can, an elongated arcuate body of thin material conforming to the arcuate curvature of the can edge, said body having a hook shaped end adapted to engage over the top edge of the opened can, and 20 a deformed lug at its opposite end adapted to inter-engage with the bottom of said can; and integral jaws intermediate its length, which jaws are reversely folded along the sides of said arcuate body and converge into pipe-stem gripping relation beyond said body.
- 25

4. In a pipe holder for use with a tobacco can, an elongated arcuate body of thin metal having a can engaging hook at one end and a can engaging lug at its opposite end, both extending inwardly toward said can, said body having oppositely disposed gripping members intermediate its 5 ends, said members converging outwardly beyond said body into relation to grip the sides of a pipe stem.

5. In a pipe holder for use with a tobacco can, 10 an elongated arcuate body of thin metal having a can engaging hook at one end and a can engaging lug at its opposite end, both extending inwardly toward said can, said body having oppositely disposed gripping jaws intermediate its 15 said ends, said jaws extending outwardly from said body and converging into relation to grip the stem of said pipe.

6. In a pipe holder for use with a tobacco can, 20 an elongated arcuate body of thin metal conforming to the arcuate curvature of the can edge, said body having a hook shaped end adapted to engage over the top edge of the opened can, and a deformed lug at its opposite end adapted to inter-engage with the bottom of said can, and 25 a plurality of oppositely disposed jaws which extend beyond said body and converge into pipe-stem gripping relation.

JOSEPH R. JACKSON. 30
